UNITED STATES PATENT OFFICE.

ORRELL ASHTON, DECEASED, LATE OF SWAMPSCOTT, MASSACHUSETTS, BY HANNAH ASHTON, EXECUTRIX, OF SWAMPSCOTT, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SHOE-TIP-MEASURING MECHANISM.

1,346,156.

Specification of Letters Patent. Patented July 13, 1920.

Application filed February 15, 1916. Serial No. 78,520.

To all whom it may concern:

Be it known that ORRELL ASHTON, deceased, late of Swampscott, in the county of Essex and State of Massachusetts, invented 5 certain Improvements in Shoe-Tip-Measuring Mechanism, of which the following description, in connection with the accompanying drawings, is a specification, like reference characters on the drawings indicating 10 like parts in the several figures.

This invention relates to apparatus for use in the manufacture of shoes, and particularly to tip measuring means designed for use in connection with the pulling-over 15 operation to enable the operative to locate the tip seam of the shoe vamp at the correct distance from the end face of the toe of the shoe. The pulling-over operation is now carried out principally by the use of 20 pulling-over machines of the type shown in United States Letters Patent No. 1,029,387, granted June 11, 1912, on application of Ronald F. McFeely.

For most advantageous use in connection 25 with the pulling-over machine the illustrative embodiment of this invention is constructed and arranged for attachment to a conveniently located support which is present in the machine and by which it is held in 30 such a position that while it is normally out of the operative's way it can be readily swung into position for measuring a shoe that is being pulled over in the machine. An important feature of this invention consists in a novel construction and arrangement 35 of instrumentalities coöperating to measure the tip of a shoe, the construction shown comprising the combination with a supporting member adapted to extend 40 lengthwise of the shoe, of a toe end abutment and a coöperating member which is adapted to be positioned at the tip seam, both said abutment and member being movable lengthwise of the shoe upon the supporting member to position them for co-operation with shoes which are of different 45 lengths or which are differently located with relation to the supporting member. In the illustrative embodiment of the invention 50 the supporting member is a longitudinally

grooved rod and the toe abutment is a plate perpendicular to the rod and provided with a sleeve which has a key located in the groove in the rod. The member coöperating with the tip seam is a plate similar to 55 the toe abutment plate but shorter, and also having a sleeve with a key fitting in the groove in the rod. A spring encircles the rod between the two plates and holds them normally apart, allowing the operative to 60 press them together for measuring or caliper 65 the work. One of the plates supports a finger which extends parallel with the supporting rod and across the other plate and has graduations marked upon it in position to be easily read by the operative for ascertaining the length of the toe tip.

The foregoing and other features of the invention, including more important details of construction and combinations of parts, 70 will be explained in connection with the following description of the illustrative embodiment of the invention and will then be pointed out in the claims.

Figure 1 of the drawings is a side elevation of the tip measurer in use. 75

Fig. 2 is an angular perspective view of the tip measurer.

In the illustrated construction the tip measurer comprises an attaching plate 2 by 80 means of which it is connected to the tack stop block 3 of the front tacker arm of a pulling-over machine, the machine of United States Letters Patent No. 1,137,564 being herein shown for illustrative purposes, 85 where it can be readily moved into operative relation to a shoe held against the sole rest 1 of the machine by the usual pulling-over grippers. The attaching plate 2 has a pivotal connection with a laterally bent arm 90 4 of a supporting rod 5. A spring 7 encircles the arm 4, being connected thereto and to the attaching plate in a way to hold the tip measuring device normally swung forwardly and upwardly against the tacker 95 arm or mechanism carried by said arm, where it is entirely out of the operative's way in carrying on the pulling-over operation.

A toe abutment plate 6 extending perpen- 100

dicularly to rod 5 has a sleeve by which it is supported to slide on the rod. The rod has a longitudinal groove and the sleeve has a key fitting in the groove to hold the 5 abutment plate in predetermined angular relation to the axis of the rod such that when the device is swung into tip measuring position the plate will extend upwardly into such relation to a shoe that it can be engaged with the toe end face of the shoe. The rod 5 also carries a second sliding plate 8 which is shorter than the toe abutment plate and is adapted in the illustrative construction to rest upon the vamp back of the 10 toe tip and be pressed forwardly against the rear edge face of the toe tip, which edge it is formed to abut against. The tip engaging member 8 is also provided with a sleeve having a key fitting in the groove 15 in the rod 5 for holding the plate 8 in parallel relation to the plate 6. A stop pin 9 in the free end of rod 5 confines the plates upon the rod. A spring 10 encircles the rod 5 between the plates 6 and 8 and presses 20 said plates normally apart. The toe abutment plate 6 is provided with a rigid finger 12 that extends parallel with the rod 5 toward and across the plate 8. The portion of the finger 12 adjacent to the plate 8 is provided with distinct graduation marks with 25 which are associated numerals, the marks being distanced from the toe abutment plate 6 to represent different standard lengths of tips and the numerals designating such 30 standard lengths. Preferably the toe abutment plate 6 is provided with a second finger 14 extending parallel with the general direction of finger 12 and guided in the plate 8, said finger 14 having a stop pin 16 in its 35 free end to limit the movement of the plates 6 and 8 apart by the spring 10.

In using this invention the supporting rod 5 is turned by the operative from its 40 up-raised position downwardly and backwardly under a shoe that has been pulled over and the tip length of which it is desired to measure or verify. It will be noted that the plates 6 and 8 and their associated devices are freely movable lengthwise of the rod 5 and that the plates are normally held apart 45 by the spring 10. As the device is swung into operative relation to the shoe, the end of the tip engaging plate 8 is made to contact with the vamp back of the tip seam, and said plates are moved forwardly until plate 8 engages the rear edge of the tip. Thereupon the toe abutment plate 6 is pressed toward the plate 8 until it abuts against the toe end face of the shoe, whereupon the operative 50 reads from the graduation marks on the finger 12 the length of the tip. If the length is not the correct one, that is, the length called for by the specification for the style

of the shoe that is being made, the operative will pull the upper, including the tip 65 seam, farther forward, or he will relieve the pull and allow the tensioned upper to slack back until the tip seam is located at the required distance from the end face of the toe, this adjustment for obtaining the right 70 length of tip being well understood in the operation of the pulling-over machine. As soon as the correctness of the length of tip has been ascertained or secured, the operative simply releases the tip measuring apparatus whereupon the spring 10 restores the plates 6 and 8 to their normal relation and the spring 7 turns the entire device into its 75 inoperative position.

The nature of the invention having been 80 explained and an embodiment thereof having been described which has been found to be efficient in use, what is claimed as new and desired to be secured by Letters Patent of the United States is:—

1. In apparatus of the class described, the combination with means for resting a shoe, of a supporting rod movable into a position where it extends lengthwise under the shoe, a plate which is slidably mounted on the 90 rod and is formed to engage the rear edge of the toe tip, a second plate slidably mounted on the rod to engage the end face of the toe, and means extending from one plate to the other for indicating the length of the tip 95 of the shoe as measured between said plates.

2. In apparatus of the class described, the combination with shoe positioning means, of a supporting rod, an attaching member upon which said rod is pivotally mounted for swinging movement into or out of a position in which it extends lengthwise of the shoe, spring means for swinging said rod to an inoperative position and against the tension of which the rod may be swung manually into operative relation to the shoe, and tip measuring devices mounted in different locations between the ends of the rod and movable together along the rod to adapt them to the position of the shoe, said devices being also movable along the rod each independently of the other for measuring the length of the tip of the shoe.

3. In apparatus of the class described, the combination with a supporting member 115 adapted to extend lengthwise of a shoe, of a plate on said member constructed and arranged to abut against the end face of the toe of the shoe, a second plate constructed and arranged to abut against the rear edge 120 face of the tip of the shoe, said plates being movable along said member each independently of the other in directions lengthwise of the shoe in response to pressure of an operative's hand against them, and yielding 125 means arranged to hold the plates normally

spaced apart while permitting them to be moved toward each other into engagement with the respective faces of the work.

4. In apparatus of the class described, a supporting member, a toe end abutment carried by the member, a second abutment carried by the member and constructed and arranged to engage against the rear edge face of the toe tip, said abutments being relatively movable lengthwise of the supporting member, means for holding the abutments yieldingly apart, and a measuring finger having a fixed relation with one abutment and a movable relation to the other abutment and provided with means for indicating visually the distance between the abutments when the abutments are in operative relation to the work.
5. In apparatus of the class described, a supporting rod, a toe abutment plate provided with a sleeve and having a key and slot connection with the rod, a tip seam abutment plate also provided with a sleeve and having a key and slot connection with the rod for maintaining the plates in parallel relation, a spring for holding the plates normally apart, and a measuring finger extending from one plate to the other to indicate the length of a tip being measured.

6. In apparatus of the class described, the combination with shoe positioning means, of an abutment plate constructed and arranged to engage the rear edge of the tip of the shoe, a second abutment plate projecting beyond said first plate heightwise of the shoe for engagement with the end face of the toe, supporting means for said plates mounted for movement to carry them into or out of operative relation to the shoe and relatively to which both plates are movable lengthwise of the shoe each independently of the other in response to pressure of an operator's hand against them, and a finger carried by one of the plates and extending across the other and provided with graduations to indicate visually the distance measured by the plates between the rear edge of the tip and the end face of the toe.

7. In apparatus of the class described, the combination with shoe positioning means, of a toe abutment plate, a tip rear edge abutment plate, supporting means for said plates relatively to which they are movable each independently of the other lengthwise of the shoe, means for yieldingly holding the plates apart a greater distance than the normal length of the tip of the shoe while permitting them to be pressed toward each other until one is made to contact with the end of the toe and the other with the rear edge of the tip, and a scale arranged to indicate visually the distance between said tip edge and toe end face.

8. In apparatus of the class described, the combination with shoe positioning means, of a supporting rod adapted for movement into position where it extends lengthwise of a shoe, and tip measuring means comprising toe end and tip edge engaging members both of which are movable longitudinally of the rod, and a graduated measuring member connected to one engaging member and extending into a relation to the other engaging member to permit tip length reading to be conveniently made.

9. In apparatus of the class described, the combination with shoe positioning means, of two gage members for measuring the length of the toe tip of the shoe, a support for positioning said members adjacent to the shoe, said members being movable each independently of the other in directions lengthwise of the shoe, spring means for normally positioning said members relatively to each other while permitting them to be moved by the operator to positions adjacent respectively to the end of the toe and the rear edge of the tip, and means for indicating visually the distance between the members.

10. In apparatus of the class described, the combination with shoe positioning means of a support movable into or out of a position adjacent to a shoe positioned by said means, two gage members mounted on said support for movement lengthwise of the shoe each independently of the other, spring means tending to separate said members while permitting them to be moved by the operator against the tension of said spring means to positions adjacent respectively to the end face of the toe and the rear edge of the toe tip, and means for indicating visually the distance between said members.

11. In apparatus of the class described, the combination with shoe positioning means, of a support movable into or out of position to extend lengthwise of a shoe positioned by said means, two gage members each mounted to slide on said support in directions lengthwise of the shoe and arranged to contact respectively with the end of the toe and the rear edge of the toe tip, spring means tending to separate said members, and means for indicating visually the distance between the members.

12. In apparatus of the class described, the combination with shoe positioning means, of two gage members for measuring the length of the tip of a shoe positioned by said means, a support for positioning said members adjacent to the shoe, said members being mounted on said support for movement each independently of the other lengthwise of the shoe, spring means tending to separate said members and against which they are movable toward each other to measure the tip,

and means connecting said members to permit them to be moved also as a unit lengthwise of the shoe.

13. In apparatus of the class described, the combination with shoe positioning means, of a supporting rod arranged to extend lengthwise of a shoe positioned by said means, two gage members each slidably mounted on said rod independently of the other for movement lengthwise of the shoe, spring means tending 10 to separate said members while permitting

them to be moved toward each other to measure the tip, and a connection between said members constructed to limit their separating movement and to position the members for movement also together as a unit along said rod. 15

In testimony whereof I have signed my name to this specification.

HANNAH ASHTON,
Executrix of the will of Orrell Ashton.
